UNITED STATES PATENT OFFICE.

ERNEST F. LUNDGREN, OF BROOKLYN, NEW YORK.

TUBE PLUG.

Application filed September 1, 1923. Serial No. 660,492.

This invention relates to tube plugs and pertains more particularly to a device adapted to plug the tubes of a steam boiler.

It is an object of this invention to provide a plug of the character described which will be simple in construction and operation, and which will form an effective closure for a leaky boiler tube.

Other objects and advantages of the invention will appear hereinafter.

A preferred embodiment of the invention selected for purposes of illustration is shown in the accompanying drawings, in which,

15 Figure 1 is an elevation of the device, the parts being shown in the relative position they would occupy when in use.

Figure 2 is an elevation showing the parts in the position in which the device is inserted in the tube,

Figure 3 is a sectional view, the position of the parts being the same as in Figure 2,

Figure 4 shows the device applied to a boiler tube,

25 Figures 5, 6 and 7 are sections on the lines 5—5, 6—6 and 7—7 respectively of Figure 3.

Figure 8 is a detail perspective view showing the split sleeves which carry the plug segments.

30 Referring to the drawings, the device comprises a spindle 1 upon one end of which is mounted a head 2 which may be fastened to the spindle in any suitable manner as by the screw thread as illustrated in the preferred embodiment shown.

The head consists of an annular flange 3 and a cone-shaped portion 4, the cone-shaped portion of the head forming a seating surface for the inside faces 5 of the plug segments 6.

40 The plug proper consists of a split cone, three of the alternate segments of which are pivoted at 7 to lugs 8 which are struck up from arms 9 which extend upwardly from a bushing 10 surrounding the spindle 1. The other three alternate segments of the plug are pivoted at 11 to lugs 12 struck up from the arms 13 which extend upwardly from a bushing 14 also surrounding the spindle 1.

45 The segments 6 are biased toward the position occupied in Figures 2 and 3 by coil spring 15 interposed between the lower ends

of each of the segments and their respective arms.

The bushings 10 and 14 are each mounted to slide on the spindle 1, and the bushing 10 is arranged to slide within the bushing 14. The arms 9 and 13 of the bushings 10 and 14 respectively are mounted alternately about the spindle and form in effect a split cylinder surrounding the same. A series of pins 16 project outwardly from the spindle 1 and slide in grooves 17 of the bushing 10. The length of the grooves 17 is limited and the ends thereof cooperate with the pin 16 to form a limit stop for the bushing 10 and 55 the segments 6 carried thereby.

The bushing 14 is biased toward the position shown in Figure 1 by a coil spring 18 surrounding the spindle 1 and enclosed within a cylindrical jacket 19 secured to the 60 spindle. A latch 20 is pivoted to the jacket 19 at 21 and is adapted to engage the upper edge of a lip 22 formed on the bushing 14 to hold the bushing in the position shown in Figure 3 against the tension of the spring. 70 A spring 23 is provided to engage the outer end of the latch to hold the latch in position to engage the bushing.

When the parts of the device are in the position shown in Figure 1, the outer surfaces of the segments 6 of the plug form a continuous cone-shaped plug, the side faces 25 of adjacent segments contact with each other, and the inner faces 5 are pressed against the cone surface 4 of the head 2 by 80 the force of the spring 18.

If the operator grasps the device, holding the sleeve 19 in one hand and the bushing 14 in the other, a downward pull on the bushing 14 against the spring 18 will move 90 the parts to the position shown in Figure 2, the frictional contact between the bushing 10 and the bushing 14 and between the faces of adjacent segments carrying the bushing 10 downwardly until stopped by the pins 16. 95 In order to provide a positive means for sliding the bushing 10 in case the friction is insufficient, the arms 13 of the bushing 14 may be undercut to form detents 13' which may engage the upper edge of the bushing 10 to draw the same downwardly. The bushing 14 may continue downwardly, how- 100

ever, until the lip 22 is engaged by the latch 20 at which time the bushing 14 will be held in its lowermost position.

It will be observed that in this position, as illustrated in Figure 2, the diameter of the split cone is less than the diameter of the cone when the parts are in the position shown in Figure 1. This enables the plug to be inserted in a tube 30 from the front end 31 thereof and is of advantage where the rear end 32 of the tube is inaccessible.

When in use, the device thus far described may be connected with an additional spindle 33 by a bushing 34 which may be secured in fixed position by a pair of nuts 35 and 36. On the other end of the spindle 33 is loosely mounted a cone 37 to plug the end 31 of the tube 30, this cone being held in position by a cone-shaped nut 38.

In operation, when it is desired to plug the tube 30 which has been found to be leaking, the parts of the plug are positioned as in Figure 2 and the plug is inserted from the end 31 of the tube 30 until the segments 25 of the cone are projected beyond the further end of the tube. The plug is then turned to a position such that the latch 20 will bear against the bottom of the tube, in order that the weight of the plug may spring the latch, allowing the segments to assume the positions shown in Figure 1. The diameter of the cone in this position is greater than the diameter of the tube, and when drawn against the end 31 of the tube, the outer surface of the cone will cooperate with the inner sides of the tube. This cooperative relation may be adjusted to any desired degree of tightness by the nut 38 on the opposite end of the spindle.

It will be observed that as the nut 38 is tightened, the adjacent faces 25 of the cone segments will be pressed into close relationship with each other and also that the faces 5 of the cone segments will be pressed into close relationship with the cone face 4 of the head 2. At the other end of the spindle the outer face 39 of the nut will cooperate with the inner face 40 of the cone 37 to form a tight joint. It will also be observed that the cone shape of the plugs at either end of the tube will force the ends of the tube outwardly toward the surrounding partitions 41, thus effectively stopping any leak which may have occurred between the tube and the partition.

When it is desired to remove the plug from the tube, the nut 38 may be loosened, and by pulling the wire 42 attached to the lug 43 struck up from the bushing 14, the segments may be moved to the position of Figure 2 and the plug withdrawn from the tube through the end through which it was inserted.

It is to be understood that the invention is not limited to the embodiment shown

herein for purposes of illustration, but that on the contrary it may be variously modified and embodied within the scope of the subjoined claims.

I claim as my invention:

1. A tube plug comprising, a split cone comprising a plurality of abutting segments, and means whereby said segments may be separated to reduce the diameter of the cone for insertion in a tube and may be restored to abutting position to increase the diameter thereof. 70

2. A tube plug comprising a split cone formed of a plurality of pivoted segments adapted to abut one against the other in substantially water-tight relationship when the plug is in operative position. 80

3. In a tube plug, a split cone comprising a plurality of pivoted abutting segments, and means to separate adjacent segments of said cone to decrease the diameter thereof. 85

4. In a tube plug, a plurality of pivoted segments having adjacent faces adapted to fit together, and having outside surfaces which form a split cone, means for separating said segments whereby said segments may pivot to reduce the diameter of the cone. 90

5. In a tube plug, a split cone, comprising a plurality of pivoted segments, means to force said segments into contact with each other, and means whereby said segments may be separated to reduce the diameter of the cone. 95

6. In a tube plug, a spindle, a head thereon, a split cone surrounding said spindle comprising a plurality of segments, a pair of bushings slidably mounted on said spindle having a plurality of arms to which said segments are pivoted, and a spring to bias said bushings toward said head. 100

7. In a tube plug, a spindle, a head thereon, a split cone surrounding said spindle comprising a plurality of segments, a pair of bushings slidably mounted on said spindle having a plurality of arms to which said segments are pivoted, a spring to bias said bushings toward said head, and a latch to hold said segments in separated position. 110

8. In a tube plug, a spindle, a head mounted thereon having a cone-shaped surface, a split cone also mounted thereon having a plurality of segments, the inside faces of said segments seating against the cone-shaped surface of the head, and adjacent surfaces of said segments seating against each other when the plug is in operative position. 115

9. In a tube plug, a split cone comprising a plurality of pivoted segments, and means for forcing said cone into contact with the end of a tube, whereby adjacent segments of said cone are forced into contact with each other, and the outside edge of the tube is caused to expand. 125 130

10. A tube plug, comprising, in combination a cone formed of a plurality of segments, separate means for carrying alternate segments of said cone, means where-
5 by one of said means and the segments carried thereby may have a relative longitudi-
nal movement with respect to the other of

said means and its segments, and means whereby said segments may have a pivotal movement with respect to their carriers. **10**

In testimony whereof, I have signed my name to this specification this 28th day of August 1923.

ERNEST F. LUNDGREN.
